Primary Examiner — Selina Sikder(74) *Attorney, Agent, or Firm* — Sander R. Geising(57) **CLAIM**

The ornamental design for a tail for a remote control, as shown and described.

DESCRIPTION

FIG. 1 is a front elevation view of the tail for a remote control, the rear elevation view being a mirror image thereof;

FIG. 2 is a side elevation view thereof;

FIG. 3 top plan view, the bottom plan view being a mirror image thereof; and,

FIG. 4 is a perspective view thereof.
